FIG. 3. C. K. E.
INVENTOR

William L. Kimerly
BY

Souther V. Moulton
ATTORNEY.

UNITED STATES PATENT OFFICE.

WILLIAM L. KIMERLY, OF GRAND RAPIDS, MICHIGAN.

COMBINED FOLDING BED AND DRESSING-CASE.

SPECIFICATION forming part of Letters Patent No. 484,765, dated October 18, 1892.

Application filed September 21, 1891. Serial No. 406,248. (No model.)

To all whom it may concern:

Be it known that I, WILLIAM L. KIMERLY, a citizen of the United States, residing at Grand Rapids, in the county of Kent and State of Michigan, have invented certain new and useful Improvements in a Combined Folding Bed and Dressing-Case; and I do hereby declare the following to be a full, clear, and exact description of the invention, such as will enable others skilled in the art to which it appertains to make and use the same.

My invention relates to improvements in a combined folding bed and dressing-case; and its object is to provide the same with certain new and useful features, hereinafter more fully described, and particularly pointed out in the claims, reference being had to the accompanying drawings, in which—

Figure 1 is a perspective view of a device embodying my invention as it appears with the bed-frame opened out; Fig. 2, a horizontal section of the dresser, showing the bed-frame in plan and partially closed, and also the same fully closed and within the case; Fig. 3, a detail in vertical section on the line 3 3 of Fig. 2.

Like letters refer to like parts in all of the figures.

A represents a dressing-case, bureau, or chest of drawers of the usual external appearance, having the usual drawers B B B and a blind or false stationary drawer front B' in place of the lower drawer, behind which is stowed away the folding-bed frame, which 35 draws out at the end of said case A and consists, essentially, of a tray C, having bottom, ends, and back secured to each other, and a detached front C', to the respective ends of which are secured the ends of the folding 40 side rails, which rails are each made in three sections F, F', and F'', the latter being secured at one end to the ends of the front C' and at right angles thereto. The middle section F' is hinged to the other end thereof at 45 G and adapted to turn inward. To the inner end of said middle section is hinged the outer end of the inner section F by hinges G', adapted to turn outward. The inner ends of said section are provided with pivot-pins K 50 at their respective upper and lower sides, which engage grooves E in the upper side of the bottom of the tray C and the lower side

of the inwardly-projecting strips D, attached to the top of each end of said tray. Said grooves E extend nearly from front to rear of 55 said tray and at their outer ends are turned outward at right angles, as shown at E'.

H H are legs pivoted to the side rails near their outer ends, which when turned down rest on the floor and support the outer end 60 of the bed-frame, the other end being supported at one side by the case A and at the other by a leg H', formed of a portion of the bottom of the tray C, pivoted to the same and adapted to turn down and engage the floor. 65 A cross-bar I is provided which is supported by cleats J on the inner side of the side rails. Said bar engaging the inner sides of said rails opposite the joints G', crowds the same outward and holds the side rails in line when 70 the bed is open and locks the same by crowding the pins K outward into the outwardly-turned ends E' of the grooves E. Any convenient bed-bottom may be provided, and an increased number of cross-bars I to support the same 75 may be inserted.

The operation of my device is obvious from an inspection of the drawings and needs no further description.

What I claim is—

1. A dressing-case or other similar article of furniture, in combination with an extensible bedstead received thereby, said bedstead comprising a tray C, having an open forward end, grooves in its bottom, and strips projecting inward from the upper ends of its sides, said strips having grooves in their under sides, said grooves having outturned ends, a detached front to said tray, and side rails hinged to the ends of said detached front and having 85 on their inner ends pivot-pins engaging and adapted to travel in said grooves, and a bar adapted to engage said side rails at the hinged parts thereof and serving to crowd said hinges outward and the pivot-pins into the outturned 90 ends of the grooves, substantially as described, 95 and for the purposes specified.

2. A dressing-case or other similar article of furniture, in combination with an extensible bedstead received thereby, said bedstead comprising a tray having an open front and adapted to slide into and out of the dressing-case and to receive the other portions of the bedstead, said tray having grooves in its bot-

tom and inwardly-projecting grooved strips, said grooves having outturned outer ends, a detached front to said tray, and the side rails made in sections F, F', and F'', said sections 5 F'' being secured at their forward ends to the ends of said detached front, said sections F' hinged at their forward ends to said sections F'', and said sections F hinged at their forward ends to said sections F' and provided at 10 their opposite ends with pins engaging and adapted to travel in the grooves in the bottom of the tray and under side of said strips, the hinges of the sections F' and F opening in opposite directions, transverse bars adapted to 15 engage said side rails opposite said hinges, and pivoted legs for said bedstead.

3. A dressing-case or other similar article of furniture having the usual drawers B and a blind or stationary false drawer B' beneath 20 said drawers B, in combination with a tray C, adapted to slide outward from behind said

false drawer through the end of the dressing-case, said tray being of substantially the same size as a drawer and having an open front side, grooves in its bottom, and grooved strips 25 projecting inward from its top, said grooves having outturned outer ends, the detached front to said tray, and folding sectional side rails connecting said front and tray, the inner section of each side rail having pivot-pins 30 engaging the grooves in the under side of the inwardly-projecting strip and in the bottom of the tray and adapted to travel therein, and transverse bars adapted to engage said side rails and lock the same in open position. 35

In testimony whereof I affix my signature in presence of two witnesses.

WILLIAM L. KIMERLY.

Witnesses:

DENNIS L. ROGERS,
LOIS MOULTON.
